HAIR CURLER

Marie R. Indahl, New York, N. Y.

Application May 5, 1934, Serial No. 724,017

6 Claims. (Cl. 132—41)

This invention relates to hair curlers, and has for its main object to provide a new and improved hair curling device for such use by private persons, that a strand of hair is clasped within and wound on and left within the device, pinned to the bulk of the hair, until the strands of hair have been dried and set, whereupon the device is opened again or left with the hair wound thereon for any certain length of time.

10 There has already been known certain hair curling devices, to be used in the manner described above, for instance, those described and illustrated in my pending United States patent application No. 677,895, but these known constructions have not proven satisfactory, due to the fact that they consist of a number of parts which require a certain amount of skill for handling the device, and which, furthermore, are liable to become entangled with the hair, so as to impede the subsequent removal of the device out of the curled hair.

15 The object of the present invention is therefore, to provide a simplified construction of such hair curling devices, which is less difficult to handle, and which will not become entangled with the curled hair.

Another important fact of this invention, is that the simplified construction of my new and improved hair curling device will make this easier 20 to manufacture and assemble, and less expensive, and therefore to be placed on the market at popular prices.

In order to carry out the objects of the invention, I have devised a construction, consisting 25 essentially of a wire made loop forming a main body with a third wire running parallel and close to and cooperating with the one leg of this loop, in order to clamp the end of a strand of hair, and consisting further of an ordinary U-shaped hair pin, which is slidably fastened within the one 30 end of the beforementioned main body, so that after winding the strand of hair on the said main body, this U-shaped hair pin may be pushed into the curled hair to fasten it temporarily to the bulk 35 of hair close to the scalp of the person using the device. In a modified construction of my device two U-shaped hair pins are slidably fastened at the two ends respectively of a main body, which latter consists of a simple loop or of two 40 parallel legs having suitable means at their ends to carry the said U-shaped hair pins.

In order that my invention may be fully understood, I have shown the before characterized embodiment of same in the drawing forming part 45 of this specification, in which drawing:

Figures 1, 2, 3, 4 are four slightly different constructions, each comprising a main body of the form of a loop with a third leg provided close to the one leg of this loop, and a block closing this loop, in combination with a U-shaped hair pin 5 slidably fastened within the said closing block.

Figure 5 is a modification of the invention, in which two U-shaped hair pins are slidably fastened within two blocks respectively, which blocks form the two ends of a main body having two 10 parallel legs.

Figure 6 is a modification in which two shorter U-shaped hair pins are slidably fastened in the two shorter sides respectively of a closed rectangular frame or legs.

Figure 7 is another modification of the invention.

Figure 8 is a modification, in which two U-shaped hair pins are slidably fastened in a rectangular frame having two end blocks hinged to 20 wire-made longer frame sides.

Figure 9 is a modification in which one U-shaped hair pin is slidably fastened in a rectangular frame consisting of one end block and a wire-made loop hinged into this end block.

Referring more particularly to the drawing, in the embodiment of the invention shown in the Figure 1, the main body of the device consists of the wire-made two-legged straight or slightly curved loop 11, and a third straight or curved 30 piece of wire 12, running close to the one leg of the loop, the ends of which loop 11 and the one end of the wire 12 being hinged in an arc or bow-shaped metallic block 13. The middle part of this block 13 has two holes bored through it 35 parallel to the legs 11 and to the wire 12, and the two shanks of a U-shaped hair pin 14 are passed slidably through the said holes of the block 13. The three free ends of the wire 12 and of the hair pin shanks 14 are provided with small enlargements or balls 15, in well known manner, so as to prevent the skin of the scalp from being hurt by the pointed ends of these wires and to prevent furthermore, the hair pin 14 from being completely pulled out of the main body. 40 The use of this new and improved hair curling device is easily understood to be as follows: With the hair pin 14 being more or less pulled back, as is shown in the Figure 1, the end of a strand of hair is slightly clamped between the wire 12 and the adjoining leg of the loop 11; then, by 45 turning the loop around its longitudinal axis, the strand of hair is wound around the main body of the device, until the device is close to the scalp of the person, and thereupon the hair pin 14 is 50

55

pushed through the cluster of the wound hair and the bulk of the rest of the hair close to the scalp.

When the hair has been dried and set, so that it will remain in the curled position, the U-shaped hair pin 14 is withdrawn from the cluster of hair, whereafter the whole device may be easily removed from the curled hair.

The construction of the embodiment shown in Figure 2 is essentially alike to that of the previous example, the only difference being, that the legs of the loop 16 and the wire 17 adjacent to the one leg 16 are hinged to a cylindrical block 18 through the middle part of which block pass the two shanks of the U-shaped hair pin 19. As in the previous case the free ends of the wire 17 and of the hair pin 19 are provided with small enlargements or balls 20. The handling and the working of this hair-curling device is likewise the same as in the previous example.

The hair curling device shown in Figure 3 has as its main body an endblock 21 of the shape of a half-circular disk, at the diametrical end of which the two-legged loop 22 and the single wire 23 are hinged, which loop and wire extend in an essentially straight forward direction, with only the closing end 24 of the loop being slightly curbed, whereas the wire 23 is shorter and straight over its whole length. A U-shaped hair pin is passed with its one shank 25 slidably through the end block 21 of the main body entering into it at the middle of its peripheric part and leaving it at the middle of its diametrical end. The other shank 26 of the U-shaped hair pin passes at the side of the end block 21. Therefore this hair pin, in addition to being slidable within the end block 21 may further be swung round its one shank 25, which fact increases the adjustability of this hair pin. For the rest the handling and the working of this hair curling device is analogous to that of the previous example.

The hair curling device shown in Figure 4, combines features of the two constructions shown in the Figures 1 and 3, in so far, as to an arcuate end block 27, a wire made loop 28 and a single wire 29 hinged, which loop and wire are shaped as described with reference to Figure 3, whereas the U-shaped hair pin 30 is joined to this main body by having its one shank only passing slidably through the middle part of the arcuate end block 27, the other shank of the hair pin passing freely at the side of this end block. The handling and working of this device is the same as before.

Attention may be called to the fact, that in all four devices shown in the Figures 1 to 4, the wire loop and the single wire adjoining the one leg of this loop are one single piece of wire, which wire is bent accordingly so as to form these two parts of the main body of the device, which construction simplifies the manufacturing of the device and reduces the cost of same. Furthermore, attention may be paid to the fact, that the hinge-forming connection of these wire-made parts with the end block of the main body results in a very great pliability of the device, which is desirable in order to fit in with more or less thick hair clusters, which may be worked upon in different cases of the application of the device.

In the embodiment of the invention shown in Figure 5 the main body of the hair curling device is made by bending a piece of wire, so as to form two side by side running legs 31, 32, united at the one side by an eyelet 33 which in a girdle-like manner, embraces an end block 34 having two holes. The two shanks of a U-shaped hair

pin 35 are slidably passed through the two holes of this end block and secured thereto by little balls at the ends of the shanks, as in the previous examples. The one leg 31 of the main body ends likewise in a small ball, whereas the other leg 32 holds, in a girdlelike manner, another end block 36, having likewise two holes through which are slidably passed the shanks of another U-shaped hair pin 37 with little balls at the ends of the shanks. In using this hair curling device a strand 10 may be clasped between the two legs 31, 32 of the main body, while the device is in wide open position as shown in Figure 4; then, after pushing the one of the two hair pins through its coordinate end block into a position side by side with the 15 main body, the strand of hair may be wound around this complex formed by this one hair pin and the main body, and finally the other hair pin is pushed through its coordinate end block into the cluster of the wound-up hair and the bulk of 20 hair close to the scalp of the person using the device.

The embodiment of the invention shown in Figure 6 has a main body consisting in a preferably wire made rectangular frame 38 with a 25 bridge 39 in its middle part. The two opposing shorter sides of this frame have each one two holes, through which holes are slidably passed the shanks of two U-shaped hair pins 40, 41 with little balls at the ends of the shanks. In 30 using this curling device with the hair pins being first drawn out of the frame, a strand of hair is wound up around the main body, 38, whereupon the two hair pins 40, 41 are pushed from both sides into the frame with the cluster of hair on 35 it, until the ends of the shanks meet over the bridge 39.

According to the embodiment of the invention shown in the Figure 7 the rectangular frame-like main body of the curling device has at its 40 one end a small bar 42 with two holes for the passage of the shanks of a U-shaped hair pin as described before. The preferably wire made legs 43, 44 of the main body and a third single wire 45 extending parallel close to the one leg 45 43 are hinged at 46 to ears provided at the two ends of the bar 42. For the rest, the construction of this curling device and its application may be exactly as that of any of the previous examples.

According to the embodiment shown in the Figure 8, a rectangular frame-like main body comprises two endblocks 47, the flanged ends of which are in hinge-connection with the two wire-made longer sides 48, 49 of the frames, 55 one of these two wires, e. g., the wire 49 being elongated so as to form an arm 50, which extends lengthwise within the frame. The shanks of two U-shaped hair pins 51, 52 are slidably passed through corresponding holes in the two 60 endblocks, respectively.

Figure 9 finally shows an embodiment of the invention, in which a rectangular frame-like main body contains one endblock 53, the flanged ends of which are in hinge-connection with a 65 wire-made angularly bent loop 54, the one end of which is elongated within the loop so as to form a longitudinally extending inner arm 55. The shanks of one U-shaped hair pin 56 are slidably passed through corresponding holes in 70 the endblock 53.

It is to be understood that the invention is not restricted to the herein described and illustrated constructions, but will include still other embodiments or variations, well within the claims, 75

and which variations will easily suggest themselves to those familiar with the art.

Having thus described my invention, what I claim as new, and desire to secure by Letters 5 Patent of the United States, is:

1. A hair curling device, comprising a frame-like main body consisting of an endblock and a two-legged loop hinged to said endblock, an arm extending close to the side of the one leg of the 10 loop, in combination with a U-shaped hair pin slidably mounted within the said endblock, and with the shanks of the pin pointing toward the loop.
15. A hair curling device, comprising a frame-like main body consisting of an endblock and a two-legged loop hinged to the endblock, an arm extending close to the side of the one leg of the loop, said arm and said loop being formed of one piece of suitably bent wire, in combination 20 with a U-shaped hair pin slidably mounted within the said endblock with the shanks of the pin pointing toward the wire-loop.
25. A hair curling device, comprising an elongated rectangular frame, in combination with two U-shaped hair pins slidably mounted in the two smaller sides of the said frame, with the shanks of the hair pins pointing toward the middle part of the said frame.
30. A hair curling device, comprising a closed elongated frame-like main body having two lon-

gitudinal legs forming a loop, the end of said loop being bent to the side, and an arm extending straight forward close to the side of the one leg of the loop, in combination with a U-shaped hair pin slidably mounted within the part of the main body opposite the loop and with the shanks of the hair pin pointing toward the loop. 5

5. A hair curling device of the class described, comprising two substantially rectangularly formed members made with downturned endportions and being adapted to have wires hingedly connected to the latter, one of said wires being made to extend in a longitudinal direction, relative to said wires, and a hair pin of a suitable shape mounted within the frame formed by the 15 said members, substantially as shown and described. 10

6. A hair curling device of the class described, comprising a substantially rectangularly formed member made with downturned endportions and being adapted to have wires hingedly connected thereto, one of said wires being made to extend in a longitudinal direction, relative to said wires a hair pin of a suitable shape mounted within the frame formed by said rectangularly shaped member, the open ended wire and hair pin being provided with ball-like enlargements upon their free ends substantially as and 20 for the purpose set forth. 25
